DESIGN FOR A TRAVELER FOR SPINNING RING

William M. Camp, Glen Ridge, N. J.

Application March 15, 1944, Serial No. 112,912

Term of patent 14 years

(Cl. D17—12)

To all whom it may concern:

Be it known that I, William M. Camp, a citizen of the United States, residing at Glen Ridge, county of Essex, and State of New Jersey, have invented a new, original, and ornamental Design for a Traveler for Spinning Ring, of which the following is a specification, reference being had to the accompanying drawing, forming a part thereof.

Fig. 1 is a side elevational view of a traveler for spinning ring showing my new design; and

Fig. 2 is a section on the line 2—2 in Fig. 1.
I claim:

The ornamental design for a traveler for spinning ring, substantially as shown.

WILLIAM M. CAMP.
